UNITED STATES PATENT OFFICE.

CLARENCE L. WILSON, OF CAMDEN, NEW JERSEY, ASSIGNOR TO JOHN H. BROMLEY
AND EDWARD BROMLEY, COPARTNERS TRADING AS JOHN BROMLEY & SONS, OF PHILADELPHIA, PENNSYLVANIA.

DESIGN FOR A RUG.

41,411.

Specification for Design.

Patented May 23, 1911.

Application filed March 22, 1911. Serial No. 616,281. Term of patent 7 years.

To all whom it may concern:

Be it known that I, CLARENCE L. WILSON, a citizen of the United States, residing in the city of Camden, State of New Jersey, have invented a certain new, original, and ornamental Design for Rugs, of which the following is a specification, reference being had to the accompanying drawing, forming part thereof.

The figure is a plan view of a Smyrna rug showing my new design.

I claim:

The ornamental design for a rug, as shown.

CLARENCE L. WILSON.

Witnesses:

H. E. HAUCK,
A. J. SNYDER.
